PLASTIC COATED FABRIC OR SIMILAR ARTICLE

Jakob H. Vogel, West Orange, N.J., assignor to Inter-
chemical Corporation, New York, N.Y., a corporation
of Ohio

Filed Sept. 17, 1959, Ser. No. 57,585

Term of patent 3½ years

(Cl. D87—4)

The figure is a plan view of a plastic coated fabric showing my new design, the repeat unit of which is substantially contained between the two horizontal dot and dash lines and the two vertical dot and dash lines.

This application is a continuation-in-part of my co-pending application, Serial No. D. 49,643, filed February 14, 1958.

I claim:

The ornamental design for plastic coated fabric or similar article, as shown and described.
